UNITED STATES PATENT OFFICE.

FRANCIS S. WALTERS, OF WILKINSBURG, PENNSYLVANIA, ASSIGNOR TO WESTINGHOUSE ELECTRIC AND MANUFACTURING COMPANY, A CORPORATION OF PENNSYLVANIA.

COMMUTATOR-SLOTTER.

1,281,724.

Specification of Letters Patent.

Patented Oct. 15, 1918.

Application filed January 7, 1914. Serial No. 810,784.

To all whom it may concern:

Be it known that I, FRANCIS S. WALTERS, a citizen of the United States, and a resident of Wilkinsburg, in the county of Allegheny and State of Pennsylvania, have invented a new and useful Improvement in Commutator-Slotters, of which the following is a specification.

My invention relates to cutting tools and 10 it has special reference to devices of this character which are adapted for cutting the insulation between the commutator bars of dynamo-electric machines.

The object of my invention is to provide 15 a simple and effective device for the purpose named, that may be readily adjusted for use with various sizes of commutator cylinders and that is light and compact.

The bars or segments of commutator cylinders for dynamo-electric machines are generally separated by sheets of mica or other hard, heat-resisting insulating material, in order that the cylinders may not be injured when subjected to high temperatures.

25 The insulating sheets are sometimes flush with the outer surface of the commutator cylinder, but, under certain conditions of service, where the wear on the commutator is likely to be excessive, better results, as 30 regards commutation, may be secured by cutting the insulation to form shallow grooves in the cylinder between the bars.

The bars and intermediate layers of insulation are substantially parallel to the axis 35 of the cylinder, but occasionally they become displaced or skewed relatively to the axis.

According to my present invention, I provide a reciprocable cutting tool having a 40 guide which may be adjusted at any desired angle to the axis of the commutator cylinder in order that the cutting tool may follow the insulation between the bars. My device is supported in such manner as to be 45 adaptable for mounting on various supports, such, for instance, as the tool carriage of a lathe or the brush holder rods of a dynamo electric machine.

My invention is illustrated in the accompanying drawing in which Figure 1 shows 50 the device mounted on a lathe, portions only of which are shown; Fig. 2 is a plan view of the device; Fig. 3 is a side elevation, partially in section, of the device shown in Fig. 55 2, and Fig. 4 is an end view of the same.

Referring to the drawings, the device here

shown comprises a cutting tool 1 of the planer type, the thickness of which corresponds to that of the insulation 2 between bars 3 of a commutator cylinder 4.

60 The tool 1 is mounted in an inclined slot 5 in a clapper box 6 in which it is rigidly maintained by a screw 7. The inclination of the tool 1, by which the cutting point is placed forward and clear of the carriage, permits a clean cut throughout the entire length of the insulation and eliminates the necessity of cutting out by hand small portions of insulation next to the commutator risers. In the usual commutator slotting 70 machines, it has been necessary to remove the insulation near the commutator risers by hand, inasmuch as the cutting tools would not permit of its removal in the regular cutting operation.

75 The clapper box 6 is pivotally mounted at an intermediate point upon a pin 10 in a groove 8 in a carriage 9, and, during the cutting stroke, is held rigidly by reason of its engagement with a face 11 of the groove 8, 80 and is adapted to be given a rotative movement about the pin 10 against the action of a spring 12 on the return stroke, in order that the tool point may yield during its return stroke and be raised if necessary out 85 of the cut. The spring 12 is located in an aperture 14 in the carriage 9 and is interposed between the carriage 9 and the end of the clapper box 6 opposite to that in which the cutting tool is mounted.

90 The base of the carriage 9, which is laterally and longitudinally extended for the purpose of providing an adequate bearing surface, is provided with a groove 17 to receive a guide or bed plate 18. A handle 19, 95 that is screwed into the side of the carriage 9, provides means by which the carriage may be moved back and forth over the bed plate 18.

95 The bed plate 18 is pivoted, at one end, 100 to a base plate 19 by a screw 20 and is provided, near its opposite end, with a slot 21 through which passes a screw 22 by means of which it may be clamped to the base plate 19.

105 The base plate 19 is provided, at one end and upon opposite sides, with lugs or brackets 23 for the reception of adjusting screws 26, the ends of which engage the edges of the bed plate 18. By manipulating the 110 screws 26, the bed plate 18 may be moved about the pivotal point, provided by the

screw 20, and rigidly fixed parallel to or at any desired angle relative to the axis of the commutator cylinder.

The base plate 19 is rigidly supported upon a standard or bracket 27 by bolts 28 which extend into holes 29 in the base plate. A plurality of the holes 29 are provided to permit the placing of the base plate in any one of several positions on the standard or bracket 27.

As shown in Fig. 1, the standard or bracket 27 is clamped to a tool post 30 of a lathe, portions only of which are shown, and adjusted so as to bring the cutting point 15 of the tool 1 in alignment with one of the strips of insulation 2 in the commutator cylinder 31 of an armature 32. The armature shaft 33 is engaged, at its ends, by head and tail spindles 34 and 35, respectively, and held in position thereby.

When the device is in position, as shown in Fig. 1, the cutting operation is performed by the operator grasping the handle 19^a and pressing to the right. The tool passes 25 through the edge of one of the layers of insulation 2 and makes the cut. With the return stroke of the handle 19^a, the tool is permitted to yield and to withdraw, if necessary, from the cut, in the manner described 30 above, thus avoiding unnecessary friction on the tool point and conserving the life of the tool. When one cut has been made, the next strip of insulation is brought into position for cutting by rotating the commutator cylinder about its axis in the lathe.

It is to be understood that my device is not restricted to use in connection with a lathe, as any device for maintaining the parts in proper relations to each other, substantially as shown in Fig. 1, may be used. My device may be mounted upon the brush holder rods of a dynamo-electric machine, in case the commutator and armature are too large for ready transposition, for which 40 purpose I provide a hole 36 and a set screw 45 37 in the member 27.

While I have shown and described a pre-

ferred embodiment of my invention and a particular adaptation thereof, the structural details and arrangement of parts may obviously be varied materially without departing from the spirit and scope of my invention, and such modifications are intended to be covered by the appended claims.

I claim as my invention:

1. A cutting device for commutator insulation comprising a reciprocable tool support, a guide therefor, a base upon which the guide is pivotally supported, and screws associated with the said base and engaging the said guide for maintaining the said guide in adjustable position.

2. A cutting device for commutator insulation including a base, a guide resting throughout substantially its entire length 65 upon the base, means for adjusting the guide angularly with respect to the base and a tool support reciprocally mounted upon the guide.

3. A cutting device for commutator insulation including a supporting base, a guide having pivoted connection with the base and resting throughout substantially its entire length against the base, means for adjusting the guide angularly with respect 75 to the base and for securing it in adjusted position and a tool support reciprocally mounted upon the guide.

4. A cutting device for commutator insulation including a base, a guide pivoted 80 at one end to the base, means cooperating between the base and the opposite end of the guide for angularly adjusting and securing the guide with respect to the base, and a tool support reciprocally mounted 85 upon the guide.

In testimony whereof I have hereunto subscribed my name this 31st day of Dec., 1913.

FRANCIS S. WALTERS.
